(57) **CLAIM**

We claim the ornamental design for a pan, as shown and described.

DESCRIPTION

The patent or application file contains at least one drawing executed in color. Copies of this patent or patent application

publication with color drawing(s) will be provided by the Office upon request and payment of the necessary fee.

FIG. 1 is a partial color drawing of a bronze color ceramic coated anodized aluminum pan having a stainless steel riveted handle in an isometric perspective view of a pan according to an exemplary embodiment of the present invention; FIG. 2 is a color drawing of a top view of the bronze color ceramic coated pan having a bronze color ceramic coating cooking surface on a pan with stainless steel handle according to an embodiment of the present invention;

FIG. 3 is a color drawing of a bottom view of a stainless steel base of an anodized aluminum pan color drawing according to an embodiment of the present invention;

FIG. 4 is an isometric drawing of the back side of the pan depicting the riveted handle attached to the according to an embodiment of the present invention;

FIG. 5 is a top orthographic view of the pan shown according to an embodiment of the present invention;

FIG. 6 is a side orthographic view of the pan according to an embodiment of the present invention;

FIG. 7 is an enlarged top orthographic view of an embodiment of the handle of the pan according to an embodiment of the present invention;

FIG. 8 is an enlarged side orthographic view of an embodiment of the handle of the pan according to an embodiment of the present invention;

FIG. 9 is another color drawing of an isometric view of a bronze color ceramic coated pan having a bronze color ceramic coating cooking surface on a embodiment of the pan with stainless steel handle according to an embodiment of the present invention;

FIG. 10 is another color drawing of an isometric view of a bronze color ceramic coated pan having a bronze color ceramic coating cooking surface on a embodiment of the pan with stainless steel handle according to an embodiment of the present invention; and,

FIG. 11 is another color drawing of a closeup view of the stainless steel handle

The bottom of the symmetric pan is flat and unornamented.
